(57) CLAIM

The ornamental design for a handbag, as shown and described.

DESCRIPTION

FIG. 1 is a top, left side, and front perspective view of a handbag showing the new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan thereof.

The broken lines in FIG. 6 illustrate an interior bottom portion of the handbag that forms no part of the claimed design.
